[57] CLAIM

The ornamental design for a universal bicycle shift lever handle, as shown and described.

DESCRIPTION

FIG. 1 is a front elevational view of a universal bicycle shift lever handle showing my new design;

FIG. 2 is a rear elevational view thereof;

FIG. 3 is a side elevational view thereof, the opposite side is a mirror image of that shown;

FIG. 4 is a top plan view thereof; and,

FIG. 5 is a perspective view thereof, on a reduced scale, it being understood that the broken lines are for illustrative purposes only and form no part of the claimed design.

FIG. 4.

FIG.2

FIG.1

FIG.3

FIG.5
